Primary Examiner — Cynthia Ramirez*Assistant Examiner* — Jeremy S. Swartz(74) *Attorney, Agent, or Firm* — Leong C. Lei(57) **CLAIM**

The ornamental design for a towel bar bracket as shown and described.

DESCRIPTION

FIG. 1 is a perspective view of a towel bar bracket showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the figures depict portions of the towel bar bracket and form no part of the claimed design.

1 Claim, 7 Drawing Sheets(56)
